L. D. MILLS AND T. B. CROWE,
CYANIDING PROCESS,
APPLICATION FILED MAR. 21, 1918.

1,387,289.

Patented Aug. 9, 1921.

UNITED STATES PATENT OFFICE.

LOUIS D. MILLS, OF SAN FRANCISCO, CALIFORNIA, AND THOMAS B. CROWE, OF VICTOR, COLORADO, ASSIGNEES TO THE MERRILL COMPANY, OF SAN FRANCISCO, CALIFORNIA, A CORPORATION OF CALIFORNIA.

CYANIDING PROCESS.

1,387,289.

Specification of Letters Patent.

Patented Aug. 9, 1921.

Application filed March 21, 1918. Serial No. 223,694.

To all whom it may concern:

Be it known that we, LOUIS D. MILLS, a citizen of the United States, residing at San Francisco, in the county of San Francisco and State of California, and THOMAS B. CROWE, a citizen of the United States, residing at Victor, Teller county, Colorado, have invented certain new and useful Improvements in Cyaniding Processes, of which the following is a specification.

The invention relates to a process for recovering cyanogen and represents improvements in cyaniding processes. The objects of the invention are to diminish the cost of cyaniding, increase its efficiency, extend its application, and render applicable the combination of it with other processes in the treatment of sundry complex ores.

Heretofore, in cyaniding processes the metal has been dissolved in a solution containing a protective excess of alkali, said excess varying in amount in accordance with the character of the metal, and the metal has been recovered from the solution by the addition thereto of a precipitant, as, for instance, zinc dust. The processes as practised have resulted in loss of much cyanogen and the practice of cyaniding has, accordingly, been expensive and practically limited to the recovery of precious metals. An important feature of the present invention consists in the recovery of the cyanogen or material parts thereof in such manner as to secure advantages indicated in the following description of the preferred embodiment, which description embraces more than will be used in many instances of actual practice and admits of much variation according to the material to be treated and the circumstances presented in particular cases.

The means and methods of bringing the metal into solution in cyanid solution are too well known to require particular description. But it may be observed that the present invention renders practicable the use of stronger solutions, particularly in treating silver ores, thus promoting greater and quicker recovery of the metal. Following any available practice of bringing the metal into solution and in most, though not necessarily all, instances after the solution has been separated from the pulp, a radical departure is made from existing practices by

freeing the cyanogen from the alkali or metal which holds it in solution, as by adding acid to the solution. The extent to which it is desirable to carry this depends somewhat upon the particular circumstances presented. In some cases all, or substantially all, the cyanogen may be freed. In other cases a part of the cyanogen may remain combined with the metal. It is usually desirable to convert all alkali and acid salts, such as cyanides, cyanates, etc., into normal or acid sulfites or corresponding compounds. A variety of acids may be used for the purpose and the one to be selected will depend chiefly upon the circumstances presented in each case. Sulfuric acid is preferred, and in some instances hydrochloric or sulfurous acid or even a substance giving a very mild acidity may serve the purpose. For instance, a cyanid solution containing silver and copper and approximately a pound of lime per ton of solution may be successfully treated by adding a ten per cent. sulfuric acid in amount sufficient to neutralize the alkalis present and create an acidity of, say, one-tenth of a pound of sulfuric acid per ton of solution.

The addition of the acid frees the cyanogen in the form of hydrocyanic gas, which tends to leave the liquid and diffuse into another gas presented to it. To remove the hydrocyanic gas from the liquid, a current of air (or other gas) is accordingly employed, and this is preferably accomplished by intimately mixing the current of air with the solution in addition to removing the hydrocyanic gas as liberated at the surface of the solution. This intimate contact of a current of air with the solution, which may be accomplished, for instance, by causing air to bubble up through the solution, speeds the process both by the agitation and by the quicker separation of the hydrocyanic gas from the liquid. It may be conveniently accomplished by placing the solution in a suitable vessel provided with a porous medium in the bottom and creating difference in pressure on opposite sides thereof by means of a vacuum. The operation is accelerated by the decreased solubility of the hydrocyanogen in the liquid at reduced pressure and in the event of a leak the gas (which is dangerously poisonous) does not escape, since the leak is inward. Without attempting an ex-

position of the chemical reactions, which is unnecessary to the successful practice of the invention, it may be remarked that the recoveries of cyanogen are, in actual operations using two cubic feet of free air per minute per ton of solution treated, over ninety-five per cent. of the free alkali cyanids present and of the cyanogen combined with zinc, where zinc has been used 10 as a precipitant.

The hydrocyanic gas freed by the addition of the acid to the cyanid solution is conducted to an absorbent thereof. In many instances such absorbent will conveniently 15 be the cyanid solution containing free alkali used as the dissolving solution. In other instances, it is more expedient to provide a separate absorbent, as, for instance, caustic soda. The absorption may be mechanically facilitated by passing the gas 20 through a porous diaphragm of a vessel or vessels containing the alkali solution or by passing it through an absorption tower into which the alkali liquor is also fed. In view 25 of the character of the gas, it is desirable to take particular precautions to secure the absorption of substantially all of it, and it is accordingly preferable to cause it to pass through a succession of absorbing mediums.

30 In practising the process, some or all the cyanogen molecules may be removed from the compounds or combinations wherein they are found in the solution. In some instances enough cyanogen will be removed 35 from the metal to cause precipitation thereof, that is, to convert the compound or combination containing the metal from a soluble to an insoluble condition. For instance, a cyanid solution containing silver may be 40 acidified, with the result that the compound NaAgCy_2 gives up half its cyanogen and becomes the simple cyanid AgCy , which is insoluble and precipitated. In such instances the practice of the invention eliminates a 45 considerable portion of the cost of precipitant and subsequent treatment as well as the cost of cyanogen, in addition to promoting greater and quicker recovery by enabling the use of stronger solutions. It will be 50 understood that in metallurgical work specific conditions vary greatly and the invention may be practised without performing all that is here recited as available.

The apparatus to be employed in practising the process will vary greatly according to the circumstances of a given situation. In the accompanying drawing is shown a flow-sheet and diagrammatic view 55 of apparatus which may conveniently be employed. The crushing of the ore in cyanid solution, followed by additional treatment and filtering, may be conducted as in ordinary practice, the filtered solution being conducted, for convenience, to storage and

the tailings or solids to waste. The solution 65 may then be conducted to a vessel A, being conveniently acidified on its way to said vessel. The vessel A is provided with a porous portion 4, and the part of the vessel separated off by said porous portion is connected 70 with an inlet, through which air or gas may be drawn into the vessel. The vessel A is connected by a pipe 5 with a vessel B of similar construction, which is connected by a pipe 6 with a vacuum pump 7, capable of 75 creating a partial vacuum or reduced pressure sufficient to cause a current of air or gas to pass through the solutions in vessels A and B, picking up the hydrocyanic gas from the solution in vessel A and carrying 80 it through an absorbent thereof in vessel B. An additional vessel C containing an absorbent of hydrocyanic gas is preferably, but not necessarily, interposed between vessel B and the vacuum pump 7 as an additional 85 precaution against any escape of the gas. The pipe through which the solution is conducted into the vessel A is preferably provided with a valve 2, controlled by a float 3. The solution is conducted from the 90 vessel A through the pipe 8 to further treatment, as filtering or precipitation, according to known practice. The air or gas carrying the hydrocyanic acid generated by the acidification of the solution is drawn 95 through an alkali solution in vessel B. Properly to maintain this alkali solution in vessel B, it is connected by means of a pipe provided with a valve, controlled by a float, with a storage tank, into which cyanid, water and lime or other alkali may be from time to time introduced, as required, which tank may supply the cyanid solution to the grinding or crushing mill. A suitable pump 10 is provided to conduct the 100 absorbent solution from the vessel B to the storage tank. It will be understood that the particular apparatus shown for purposes of illustration is merely one form of apparatus which may be used in practising 110 the invention and that other forms may also be used in practising the invention as circumstances may indicate.

While, for the sake of clearness, the cyanid treated by the invention has been referred to as in a solution and the invention will commonly be practised with the cyanid in that form, it is to be understood that in some cases the cyanid solution from which the cyanogen is recovered will be present 115 as moisture in the residue pulp of decantation processes or in the cake of filters or other places where the comparative amount of liquid is small, and in such applications of the invention it will be convenient to 120 add more liquid to effect its convenient practice.

The invention makes practicable the cy-

aniding of ores from which the metal has not heretofore been profitably recoverable and extends the profitable application of cyanid processes.

5 It will be understood that the invention may be practised without carrying out all that is here recited, since specific conditions in metallurgical work vary greatly. All the variations which will suggest themselves to those skilled in the art as made desirable by the circumstances of a given situation are contemplated and covered by the following claims:

1. A cyaniding process comprising dissolving metal in cyanid solution, adding acid to said solution to generate hydrocyanic acid gas, connecting the surface of the solution with an alkali absorbent of cyanogen by a connection which excludes the atmosphere, admitting air to the bottom of the solution, establishing beyond said absorbent a partial vacuum to draw the air through said solution to pick up the hydrocyanic acid gas therefrom and through said

absorbent to absorb said hydrocyanic acid 25 gas.

2. A process for recovering cyanogen from materials used in cyaniding processes, comprising adding acid to a solution thereof to liberate hydrocyanic acid gas therefrom, 30 subjecting the solution to a vacuum to draw said gas therefrom, and conducting said gas to an absorbent of cyanogen.

3. A process for recovering cyanogen from materials used in cyaniding processes 35 comprising adding acid to a solution of material comprising cyanogen, liberating hydrocyanic acid gas in the solution, subjecting the solution to a vacuum, permitting another gas to enter the solution to draw 40 and wash therefrom the hydrocyanic acid gas, and conducting said gases into contact with an absorbent of cyanogen.

In witness whereof, we have hereunto set our signatures.

LOUIS D. MILLS.
THOMAS B. CROWE.
